UNITED STATES PATENT OFFICE.

ANDREW BENSON, OF CHICAGO, ILLINOIS, ASSIGNOR TO LEWIS E. CURTIS, OF CHICAGO, ILLINOIS.

PROCESS OF CUTTING SHEET METAL.

No. 901,772.

Specification of Letters Patent.

Patented Oct. 20, 1908.

Application filed January 27, 1908. Serial No. 412,694.

To all whom it may concern:

Be it known that I, ANDREW BENSON, a citizen of the United States, residing in Chicago, in the county of Cook and State of Illinois, have invented a new and useful Improvement in Processes of Cutting Sheet Metal, of which the following is a specification.

In the slitting of sheet metal preparatory to expanding it, the machines employed have in some cases embodied two pairs of slitting rolls located with one pair in advance and acting slightly before the other. These rolls are equipped with coacting cutters, extending the entire width of the sheet, such cutters being spaced apart on the rolls a distance equaling the width of two strands of the expanded metal. The cutters have interrupted or broken peripheries so that they make slits instead of continuous cuts in the metal, and the slits made by the cutters upon the second pair of rolls are located in planes equidistant between and alternating with those made by the cutters of the first pair of rolls, and in staggering positions relative to the latter. In the use of these machines, difficulty has been encountered especially in slitting heavy metal, owing to the curling, bending and distorting and loss of position of the strips formed in the metal by the first pair of rolls before the second pair of rolls begins to operate upon them. This curling, bending etc., occasions such serious irregularities in the cuts made by the second pair of rolls, as to render the sheets unfit for use.

To remedy this difficulty has been my object in the present invention, and I accomplish it by the use of the method now to be described.

Instead of cutting alternate rows of slits one in advance of the other, and instead of staggering the slits as stated, I first slit the sheet from side to side with slits of a uniform length spaced apart the width of a single strand only, and all substantially co-extensive in the same zone or transverse section of the sheet, then leaving a transverse uncut zone or section of the sheet (and which may appropriately be called the bond section because the bonds between the strands of the completed sheet are formed from it). I slit another transverse zone of the sheet with slits similar to those first mentioned and in alignment therewith; then leaving a second transverse bond section, I slit a third trans-

verse zone in the same manner, and follow it with a third bond section, and continue thus forming the slitted sections and the bond sections alternately until the end of the sheet is reached. I then connect the alternate pairs 60 of slits (counting from the side of the sheet) upon opposite sides of each bond section with each other by cutting through the alternate bond sections and when the connecting cuts have been made the slitting operation is 65 complete and the sheet is ready for expanding. Proceeding lengthwise of the sheet along a line of the slits mentioned, every other bond portion is left uncut, so that the cut parts of the bond portions alternate with 70 uncut parts both longitudinally and laterally of the sheet, as shown in Figure 5.

In the accompanying drawing, I illustrate the operation described and also show a suitable construction of slitting rolls which may 75 be employed.

In said drawing, Fig. 1 shows a vertical section of the slitting rolls; Figs. 2 and 3 are face views of said rolls; Figs. 4 and 5 show a sheet of metal as it appears in the different 80 stages of the slitting process, and Fig. 6 shows the sheet after expanding.

In said drawing, 6 represents a sheet of metal undergoing the slitting operations of my process, and the same is shown in Fig. 4 85 as it appears after being subjected to the initial or first operation of the process, and in Fig. 5 as it appears after the completion of the slitting. A suitable construction of rolls which may be employed in the performance 90 of my process is shown in Figs. 1, 2 and 3, but it will be understood that my process is in no wise dependent upon use of such or similar rolls, nor limited to the use of the same.

The first step of my process is the slitting of transverse sections or zones 7, 8, 9, 10 and 11 of the sheet separated from each other by the uncut bond zones or bands 12, 13, 14 and 15. The slits which are shown at 16 and 17 100 are of uniform length and separated from each other by the width desired for the strands of the expanded metal, and those of each slitted section are arranged in a series extending from edge to edge of the sheet, and with their ends in the same transverse planes the slits of all the sections are in alignment. The bond zones are narrow and of a width corresponding to the length of the bonds in the completed metal. In the 110

performance of this step of the process, I preferably employ cutting rolls 20 20, the series of cutters 21 of which are adapted to form the slits through the entire width of 5 the sheet. The cutters are notched at 22 so that they do not operate upon the bond sections or zones.

The next step of the process consists in forming cuts through the bond sections connecting alternate slits at each side thereof. Thus referring to Fig. 5, it will be seen that all the slits 16 of slotted sections 7 and 8 are united by cuts through bond section 12; that the slits 17 of sections 8 and 9 are united in a 15 similar manner through bond section 13; that slits 16 of sections 9 and 10 are similarly united through bond section 14 and so on through the whole sheet, the alternate slits counting from the edge of the sheet being 20 united by cuts through the alternate bonds. Appropriate cutting rolls 23 are shown for effecting these cuts through the bond sections. They are provided with flat sides 24 provided with properly spaced counteracting 25 cutters 25 adapted to act on alternate bonds only. By this manner of slitting, I obtain the benefit in the first step of the process attending the use of closely associated knives operating upon the solid sheet and preventing 30 the difficulty to which I have referred. After the slits 16 and 17 have been united as described, they are of course double their original length with the width of the bond section added, and the strands thus formed 35 are united by the uncut alternate bond sections. The fabric produced by the opening of the sheet is shown at Fig. 6.

I claim:

1. The improvement in the process of preparing sheet metal for expanding, consisting in first forming alined slits in longitudinally separated sections of the sheet, and then uniting alining slits of adjacent sections by cutting the separating bonds, alternating the 45 cuts both transversely and lengthwise of the sheet.

2. The improvement in the process of preparing sheet metal for expanding, consisting in first dividing the sheet into slotted sections with uncut separating sections, the slits being uniform in length and not staggered but in uniform alinement, and then uniting the slits of adjoining sections by cutting the separating sections alternately both transversely and longitudinally of the sheet. 55

3. The improvement in the process of slitting sheet metal preparatory to expanding it, consisting in first slitting transverse sections or portions of the sheet with uniform alined slits spaced the width desired for the strand 60 in the completed article, leaving uncut bond portions between the sections, and then uniting the alternate slits of adjoining sections by cutting the bond portions alternately both transversely and lengthwise of 65 the sheet.

4. The improvement in the process of slitting sheet metal preparatory to expanding it, consisting in first forming a plurality of series of alined slits of uniform length and 70 spaced apart to correspond to the width of the strands in the completed article, and then uniting the alternate slits of adjacent sections by cutting through the alternate bond portions, these cuts being alternated 75 both transversely and lengthwise of the sheet.

5. The herein described process of preparing sheet metal for expanding, consisting in first cutting the sheet to form sections of narrow parallel strips, the separating slits between the said strips of different sections being cextensive and in alinement, and then cutting the bond portion remaining between the said sections to unite alternate slits of adjacent sections, alternating the cuts transversely and lengthwise, throughout the sheet. 80 85

ANDREW BENSON.
